Primary Examiner — T. Chase Nelson*Assistant Examiner* — Mark Cavanna(74) *Attorney, Agent, or Firm* — Myers Bigel Sibley & Sajovec(57) **CLAIM**

The ornamental design for a biometric monitor housing, as shown and described.

DESCRIPTION

FIG. 1 is a front perspective view of a biometric monitor housing, showing our new design;

FIG. 2 is a front view thereof;

FIG. 3 is a rear view thereof, opposite that shown in FIG. 2;

FIG. 4 is a side view thereof;

FIG. 5 is a side view thereof, opposite that shown in FIG. 4;

FIG. 6 is a top view thereof; and,

FIG. 7 is a bottom view thereof, opposite that shown in FIG. 6.

The broken lines are included for the purpose of illustrating unclaimed portions of the biometric monitor housing and form no part of the claimed design.
